PROCESS FOR MECHANICALLY OPENING
THE BRANEfraim Rabinowitsch, Paris, France, assignor to
Nomolas Limited, London, EnglandNo Drawing. Application September 20, 1932,
Serial No. 634,081. In Germany September 23,
1931

1 Claim. (Cl. 83—28)

Processes for mechanically opening the bran by intensive milling are well known.

The milling of the tough and resisting substances of the peripheral layers of the grain, however, required a tremendous power which caused such a rise of temperature, that the enzymatic properties were lost completely. The albumen in the gel condition was caused to coagulate and the final product was so to say milled 10 dead.

The known process of mechanically opening the bran by wet milling has had little success only, because, as will be explained later on, it is impossible to cause the aleurone cells to swell by 15 softening the bran, even by softening in lime-containing water, without which swelling the milling is, as far as the opening of the aleurone cells comes into consideration, of nearly no use.

The process according to the invention differs 20 from the processes known and described hitherto in this, that the bran is subjected to a mechanical milling not in a wet condition only, but also in a swollen condition, whereby the disadvantages of the dry milling are completely avoided and an 25 opening of the aleurone cells which have been caused to swell, is obtained in such a manner, that the valuable albumen and lipoids are made available.

If the aleurone cell of the dead-ripe grain is 30 examined, it will be noted, that the fat-containing interior of the cell is completely filled with albumen in the gel condition and surrounded by a very strong and resisting husk, representing a semi-permeable diaphragm.

If the cell is brought into contact with an excess of water, the albumen in the gel condition, contrary to expectation, cannot be caused to swell.

The reason for this is, that, even if only a 40 trace of water has come into contact with the albumen, the change of the albumen from the gel to the sol condition begins. This process, however, is accompanied by a tremendous increase of volume. The strong husk offers considerable resistance to this effort of expansion, whereby the pressure in the interior of the cell is increased to such an extent, that the further penetration of water is rendered impossible.

This also is the reason for the fact, that the 50 aleurone layer cannot be digested by the human

stomach and that Professor Lindner came to the following conclusion: "The aleurone cells pass the alimentary canal like soldered tins which do not give off any of their contents. If the cells would not have such thick walls which resist the chyle, they would represent a very valuable addition in the bread." 5

For this reason it is, moreover, impossible to mechanically open the dry or the wet aleurone cell which only is obtained by milling cells which have 10 been caused to swell.

To cause in aleurone cells the swelling of the albumen in the gel condition, it is sufficient, to exert a pressure upon the water which permanently is greater than the continuously increasing 15 interior pressure of the aleurone cell caused by the swelling of the albumen.

This may easily be obtained by introducing the bran together with water in excess into a closeable vessel and subjecting these substances to a continuously increasing pressure, whereby, in spite 20 of the increasing pressure in the interior of the cell, always fresh water is introduced to cause further swelling of the albumen.

After this treatment only the bran is subjected 25 to a mechanical milling and the "soldered tins" are opened, because now, during the compression of the cell between the rollers, the albumen, rendered movable, is more and more compressed upwardly, whereby the final result is obtained, that 30 the cell which has been caused to swell, is torn.

The material treated in this manner may then, together with a corresponding amount of flour, either in wet condition or after drying, directly be baked to wholemeal bread or be used for pastes 35 or fodder purposes.

What I claim is:

A process for mechanically opening bran, having albumen containing cells surrounded by tough aleurone layers which consists in introducing 40 bran and an excess of water into a closeable vessel, producing a continuously increasing pressure in said vessel to cause a portion of said water to penetrate into said cells, keeping said pressure permanently higher than the pressure produced in the interior of said cells by contact of the water with the albumen, whereby said cells and said aleurone layers are caused to swell, and 45 milling said cells in the swollen condition.

EFRAIM RABINOWITSCH. 50
